(57) CLAIM

The ornamental design for a utensil rest, as shown and described.

DESCRIPTION

FIG. 1 is a top perspective view of a utensil rest in accordance with the present design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view showing the utensil rest in its environment.

The broken lines shown in the drawings illustrate portions of the utensil rest and environment, and form no part of the claimed design.

1 Claim, 5 Drawing Sheets
